FRANK C. ANDERSON, OF CINCINNATI, OHIO, ASSIGNOR TO THE AMERICAN VALVE & METER COMPANY, OF CINCINNATI, OHIO, A CORPORATION OF OHIO.

SWITCH-STAND CRANK MECHANISM.

1,169,106.

Specification of Letters Patent. Patented Jan. 25, 1916.

Application filed August 7, 1915. Serial No. 44,165.

To all whom it may concern:

Be it known that I, FRANK C. ANDERSON, a citizen of the United States, and a resident of Cincinnati, in the county of Hamilton 5 and State of Ohio, have invented certain new and useful Improvements in Switch-Stand Crank Mechanism, of which the following is a specification.

My invention relates to switch stands; and 10 its object is to render the switch stand interchangeable for use on either the right or left hand side of the track, and for a turnout in either direction, whereby it may be locked over the front head-block in any of these 15 installations, *i. e.*—locked on the side of approach into the turnout, thus permitting more uniformity and convenience in general, in the installation and operation of switches.

With the above purposes in view my invention 20 consists in the improved crank and crank mechanism hereinafter set forth and claimed.

In the drawing: Figure 1 is a plan view of a switch stand with my improved crank 25 mechanism applied thereto; Fig. 2 is a front elevation of the same; Fig. 3 is a vertical sectional side elevation of the same, the section being taken on a line corresponding to the line $x-x$ of Fig. 2; Fig. 4 is a detail 30 perspective view of the crank; Fig. 5 is a view similar to Fig. 3, showing a modification; and Fig. 6 is a detail perspective view of the modified head.

The switch stand here shown to exemplify 35 the use of my invention comprises the frame 1 with the top plate 2, which has the two notches 3 and 4, 180° apart and adapted to be alined substantially parallel with the track rail and having a backward extension 40 5 with a third notch 6 midway between or 90° from the other two notches 3 and 4 and opening outwardly at right angles to the track rail. A shaft 7 is journaled vertically in the frame 1 and has a fulcrum head 8, 45 fixed upon it to swing around over the top plate 2, while this fulcrum head 8 has a switch-operating lever 9 pivoted in it to swing in a substantially vertical plane from a vertical position in which it is shown in 50 the drawing, to a horizontal position, and, when in the vertical position, to occupy any of the notches 3, 4 or 6, and to swing out of the notches into the horizontal position and allow the fulcrum head to be swung

around, turning the shaft 7 with it. As here 55 shown, the shaft is rotated through an angle of 180° to throw the switch.

The connecting rod 10 extends from the crank of the switch stand over toward the track between the head blocks 11 and 12, to 60 which the feet 13 and 14 of the frame 1 are secured, and is connected with the point rails in a well known manner. In order that the switch-operating lever 9 may have closed the switch when it has dropped into the notch 65 3 or 4, depending upon whichever side the switch turns out upon, it is necessary to provide for two different adjustments of the crank with respect to the shaft 7; and, since the switch stand may be located on one or 70 the other side of the track, it is necessary to provide two adjustments for this reason in connection with either one of the above reasons. It is highly desirable that it be possible to order any quantity of the switch 75 stands and use them in any one of the four positions demanded in the service. It is in the crank of the switch stand that I provide means for enabling the above convenience to be attained. I accomplish this purpose 80 by providing the lower end of the shaft 7 with a substantially rectangular head 15 which has openings 16 through it horizontally at right angles to each other. The head 15 may be forged on the end of the 85 shaft 7 and the openings 16 may be bored therethrough.

The crank 17 comprises a head 18 with an upright part 19 and a horizontal part 20 extending in one direction from the bottom 90 of the part 19 so that this head 18 is thus substantially L-shaped in this respect. It has a rib 21 that braces the two parts 19 and 20 with respect to each other. Projecting down from the bottom of the lower horizontal part 20 is the crank pin 22 having on its lower end a flat head 23. Projecting from the side of the upright part 19 in direction opposite from the projection of the lower part 20 is a shank 24 which is adapted 100 to fit into and extend through either one of the horizontal openings 16 through the head 15 of the shaft 7. Also projecting from the head 18 in the direction of the shank 24 but at the bottom opposite from the part 20 is 105 a lip 25 that will come snugly under the lower side of the shaft head 15. The shank 24 is threaded for a considerable distance

inward from its end, and when it is passed through the shaft head 15 as above described, a nut 26 is screwed onto this shank 24 to hold the crank 17 on the shaft head 15. A cotter pin 27 is passed through the nut 26 and through an opening 28 in the shank 24 to prevent the nut from being screwed off the shank. Between this nut 26 and the adjacent side of the shaft head 15 a 10 number of washers 29 may be interposed, as shown in Figs. 1 and 3.

The connecting rod 10 has a crotch 30 on its end to fit up against a side of the crank pin 22 between the lower side of the crank head 18 and the head 23 of the crank pin 22 and when the rod 10 is in this position a U-shaped strap 31 is passed over the crank pin 22 with its side parts flanking the rod 10 near its end, and bolts 32 are passed 20 through openings in the side parts of the strap 31 and through the rod 10, as shown in Fig. 3, holding the strap rigidly to the rod. Thus the bearing of the connecting rod 10 on the crank pin 22 is made up of the crotch 30 and the part of the strap 31 that extends around the other side of the crank pin, as is best seen in Fig. 1.

The entire crank comprising the head 18, with its two parts 19 and 20 and rib 21 and 30 the crank pin 22 with its head 23 and the shank 24 and the lip 25 are all formed integrally of cast steel or of a steel forging.

The purpose of the lip 25 engaging with the lower side of the shaft head 15 is to prevent turning of the crank in the opening 16 in which it is inserted. From the foregoing it will be seen that the crank 17 may be made to have four different positions with respect to the shaft 7 by inserting the 40 shank 24 through either one of the openings 16 in either direction. Furthermore, when the washers 29 are interposed between the nut 26 and the shaft head 15 the radius of the crank may be very readily adjusted by 45 transferring one or more of these washers 29 to the other side of the shaft head 15 between it and the crank head 18. Thus adjustment of the radius or throw of the crank may be made to compensate for wear or to 50 make the switch stand suitable for different switches having the point rails thrown different distances.

While thus providing for ready adjustment for the purposes hereinbefore pointed 55 out, and also for ready adjustment of the throw of the crank when the washers are used, there is, nowhere, in the construction of the crank on its fastening to the shaft 7 any part that is liable to become loose 60 and allow the parts to become detached and inoperative. Therefore, while affording great convenience, there is also afforded a high degree of safety and efficiency in this important part of a switch stand.

65 In the modification shown in Fig. 5, the

crank 17' has the head 18' and the shank 24' separate, the shank being in the form of a pin with a head 24''. This head 18', like the head 18, comprises the upright part 19' and the lateral part 20 which, however, are provided with two ribs 21' at opposite sides, so that the head 24'' of the shank or pin 24' may come between them against the upright part 19', in which is an opening 33 through which the shank 24' passes.

70 It will be understood that this crank may be otherwise like the crank 17 of the preceding example, with the advantage of dispensing with the need of finishing the shank in behind the lip 25', offsetting the disadvantage of having the crank made thus in two pieces; and at the same time, all of the advantages of adjusting for different positions and of adjusting the radius or throw of the crank are available as with the device 75 of the preceding example.

80 Although I show my invention applied to a switch stand for operation through an angle of 180°, it will be understood that it is equally suitable for operation through only 90°, as when the lever 9 occupies the intermediate notch 6 in open position.

85 Having fully described my invention, what I claim as new and desire to secure by Letters Patent is:

90 1. In switch stand crank mechanism, in combination with a switch stand, means operatively connecting the switch stand to the switch comprising a shaft and a crank, means for connecting said crank to said shaft in any one of four positions according to the position of the switch stand relative to the switch and to the direction of turnout of the switch.

95 2. In switch stand crank mechanism, in combination with a switch stand, means operatively connecting the switch stand to the switch comprising a shaft and a crank, means for connecting said crank to said shaft in any one of four positions according to the position of the switch stand relative to the switch and to the direction of turnout of the switch, and comprising a connecting rod, a crank pin integral with said crank, a head on said crank pin integral with said crank pin, and a strap holding the end of said connecting rod to said crank pin between said crank and said head of said crank pin.

100 3. In switch stand crank mechanism, in combination with a switch stand, means operatively connecting the switch stand to the switch comprising a shaft and a crank, means for connecting said crank to said shaft in any one of four positions according to the position of the switch stand relative to the switch and to the direction of turnout of the switch, and a series of spacing means between said shaft and said connecting means of said crank adapted to be variously 105 110 115 120 125 130

positioned with respect to said shaft, and connecting means to vary the radius or throw of said crank.

4. In switch stand crank mechanism, in combination with a switch stand comprising a switch-operating shaft, a head on said shaft having openings through it in two different directions, a crank having a shank adapted to extend through either one of the openings in either one of two directions, and means for holding said shank in the opening in which it is inserted.

5. In switch stand crank mechanism, in combination with a switch stand comprising a switch-operating shaft, a head on said shaft having openings through it in two different directions, a crank having a shank adapted to extend through either one of the openings in either one of two directions, 20 means for holding said shank in the opening in which it is inserted, and a projection on said crank engaging with a side of said head to prevent the turning of said crank with its shank in the opening.

25 6. In switch stand crank mechanism, in combination with a switch stand comprising a switch-operating shaft, a head on said shaft having openings through it in two different directions, a crank having a shank 30 adapted to extend through either one of the openings in either one of two directions, means for holding said shank in the opening in which it is inserted, and a crank pin integral with said crank.

35 7. In switch stand crank mechanism, in combination with a switch stand comprising a switch-operating shaft, a head on said shaft having openings through it in two different directions, a crank having a shank
40 adapted to extend through either one of the openings in either one of two directions, means for holding said shank in the opening in which it is inserted, a crank pin integral with said crank, a head on said crank
45 pin integral with said crank pin, a connecting rod having an end against said crank pin between the crank and the head of the crank pin, and a strap passing around the crank pin and secured to said connecting
50 rod between said crank and said head of said crank pin.

8. In switch stand crank mechanism, in combination with a switch stand comprising a switch-operating shaft, a head on 55 said shaft having openings through it in two different directions, a crank having a shank adapted to extend through either one of the openings in either one of two directions, means for holding said shank in the 60 opening in which it is inserted, a projection on said crank engaging with a side of said head to prevent the turning of said crank with its shank in the opening, and a crank pin integral with said crank.

9. In switch stand crank mechanism, in

combination with a switch stand comprising a switch-operating shaft, a head on said shaft having openings through it in two different directions, a crank having a shank adapted to extend through either one of the 70 openings in either one of two directions, means for holding said shank in the opening in which it is inserted, a projection on said crank engaging with a side of said head to prevent the turning of said crank with 75 its shank in the opening, said shank and said projection being integral with said crank.

10. In switch stand crank mechanism, in combination with a switch stand comprising a switch-operating shaft, a head on said shaft having openings through it in two different directions, a crank having a shank adapted to extend through either one of the openings in either one of two directions, means for holding said shank in the opening in which it is inserted, a projection on said crank engaging with a side of said head to prevent the turning of said crank with its shank in the opening, and a crank pin integral with said crank, said shank and said projection being integral with said crank and crank pin. 80 85 90

11. In switch stand crank mechanism, in combination with a switch stand comprising a switch-operating shaft, a head on said shaft having openings through it in two different directions, a crank having a shank adapted to extend through either one of the openings in either one of two directions, threads on the end part of said shank, and a nut screwed onto said threads toward said head to hold said crank to said shaft. 95 100

12. In switch stand crank mechanism, in combination with a switch stand comprising a switch-operating shaft, a head on said shaft having openings through it in two different directions, a crank having a shank adapted to extend through either one of the openings in either one of two directions, 105 threads on the end part of said shank, a nut screwed onto said threads toward said head to hold said crank to said shaft, and a series of washers interposed between said nut and said head, one or more of which may 110 be transferred to the opposite side of said head between it and the crank, whereby the radius or throw of said crank may be adjusted. 115

13. In switch stand crank mechanism, in combination with a switch stand comprising a switch-operating shaft, a head on said shaft having openings through it in two different directions, a crank having a shaft adapted to extend through either one of the openings in either one of two directions, threads on the end part of said shank, and a nut screwed onto said threads toward said head to hold said crank to said shaft, and a projection on said crank engaging with a 130 120 125

side of said head to prevent the turning of said crank with its shank in the opening.

14. In switch stand crank mechanism, in combination with a switch stand comprising a switch-operating shaft, a head on said shaft having openings through it in two different directions, a crank having a shank adapted to extend through either one of the openings in either one of two directions, threads on the end part of said shank, a nut screwed onto said threads toward said head to hold said crank to said shaft, and a crank pin integral with said crank.

15. In switch stand crank mechanism, in combination with a switch stand comprising a switch-operating shaft, a head on said shaft having openings through it in two different directions, a crank having a shank adapted to extend through either one of the openings in either one of two directions, threads on the end part of said shank, a nut screwed onto said threads toward said head to hold said crank to said shaft, a crank pin integral with said crank, a head on said crank pin integral with said crank pin, a connecting rod having an end against said crank pin between the crank and the head of the crank pin, and a strap passing around the crank pin and secured to said connecting rod between said crank and said head of said crank pin.

16. In switch stand crank mechanism, in combination with a switch stand comprising a switch-operating shaft, a head on said shaft having openings through it in two different directions, a crank having a shank adapted to extend through either one of the openings in either one of two directions, threads on the end part of said shank, a nut screwed onto said threads toward said head to hold said crank to said shaft, a projection on said crank engaging with a side of said head to prevent the turning of said crank with its shank in the opening, and a crank pin integral with said crank.

17. In switch stand crank mechanism, in combination with a switch stand comprising a switch-operating shaft, a head on said shaft having openings through it in two different directions, a crank having a shank adapted to extend through either one of the openings in either one of two directions, threads on the end part of said shank, a nut screwed onto said threads toward said head to hold said crank to said shaft, and a series of washers interposed between said nut and said head, one or more of which may be transferred to the opposite side of said head between it and the crank, whereby the radius or throw of said crank may be adjusted, and a projection on said crank engaging with a side of said head to prevent the turning of said crank with its shank in the opening.

18. In switch stand crank mechanism, in

combination with a switch stand comprising a switch-operating shaft, a head on said shaft having openings through it in two different directions, a crank having a shank adapted to extend through either one of the openings in either one of two directions, threads on the end part of said shank, a nut screwed onto said threads toward said head to hold said crank to said shaft, a series of washers interposed between said nut and said head, one or more of which may be transferred to the opposite side of said head between it and the crank, whereby the radius or throw of said crank may be adjusted, and a crank pin integral with said crank.

19. In switch stand crank mechanism, in combination with a switch stand comprising a switch-operating shaft, a head on said shaft having openings through it in two different directions, a crank having a shank adapted to extend through either one of the openings in either one of two directions, threads on the end part of said shank, a nut screwed onto said threads toward said head to hold said crank to said shaft, a series of washers interposed between said nut and said head, one or more of which may be transferred to the opposite side of said head between it and the crank, whereby the radius or throw of said crank may be adjusted, a crank pin integral with said crank, a head on said crank pin integral with said crank pin, a connecting rod having an end against said crank pin between the crank and the head of the crank pin, and a strap passing around the crank pin and secured to said connecting rod between said crank and said head of said crank pin.

20. In switch stand crank mechanism, in combination with a switch stand comprising a switch-operating shaft, a head on said shaft having openings through it in two different directions, a crank having a shank adapted to extend through either one of the openings in either one of two directions, threads on the end part of said shank, a nut screwed onto said threads toward said head to hold said crank to said shaft, and a series of washers interposed between said nut and said head, one or more of which may be transferred to the opposite side of said head between it and the crank, whereby the radius or throw of said crank may be adjusted, a projection on said crank engaging with a side of said head to prevent the turning of said crank with its shank in the opening, and a crank pin integral with said crank.

21. In switch stand crank mechanism, in combination with a shaft, a rectangular head formed on said shaft integral therewith and having openings through it at right angles to each other and at right angles to the axis of the shaft, and a crank comprising a head having a vertical part and a horizontal part extending from said

- vertical part near its lower end in one direction, a crank pin extending from the lower side of said horizontal part downward, and a head on the lower part of said crank pin, 5 a shank extending from said vertical part in direction opposite from that of the horizontal part and adapted to pass through either one of said openings in said shaft head in either direction, a lip extending 10 from said crank head in the same direction as the extension of the shank and adapted to engage with the lower side of said head to prevent the crank from turning with its shank in the opening in the shaft head, 15 threads on the end part of said shank, and a nut screwed on said threads toward said shaft head to hold said crank to said shaft.
22. In switch stand crank mechanism, in combination with a shaft, a rectangular head formed on said shaft integral therewith and having openings through it at right angles to each other and at right angles to the axis of the shaft, and a crank comprising a head having a vertical part 25 and a horizontal part extending from said vertical part near its lower end in one direction, a crank pin extending from the lower side of said horizontal part downward, and a head on the lower part of said crank pin, 30 a shank extending from said vertical part in direction opposite from that of the horizontal part and adapted to pass through either one of said openings in said shaft head in either direction, a lip extending 35 from said crank head in the same direction as the extension of the shank and adapted to engage with the lower side of said head to prevent the crank from turning with its shank in the opening in the shaft head, 40 threads on the end part of said shank, a nut screwed on said threads toward said shaft head to hold said crank to said shaft, and a series of washers around said shank between said nut and said shaft head, one 45 or more of which may be transferred to a position around said shank between said shaft head and the vertical part of said crank head, whereby the radius or throw of the crank may be varied.
- 50 23. In switch stand crank mechanism, in combination with a shaft, a rectangular head formed on said shaft integral therewith and having openings through it at right angles to each other and at right angles to the axis of the shaft, and a crank comprising a head having a vertical part 55 and a horizontal part extending from said vertical part near its lower end in one direction, a crank pin extending from the lower side of 60 said horizontal part downward, and
- a head on the lower part of said crank pin, a shank extending from said vertical part in direction opposite from that of the horizontal part and adapted to pass through either one of said openings in said shaft 65 head in either direction, a lip extending from said crank head in the same direction as the extension of the shank and adapted to engage with the lower side of said head to prevent the crank from turning with its shank in the opening in the shaft head, threads on the end part of said shank, a nut screwed on said threads toward said shaft head to hold said crank to said shaft, and a connecting rod abutting said crank pin between the lower side of said crank head and the crank pin head, and a strap extending 70 around the crank pin and having side parts flanking the connecting rod, and bolts through said connecting rod and said side parts, whereby said connecting rod is pivotally held to said crank.
24. In switch stand crank mechanism, in combination with a shaft, a rectangular head formed on said shaft integral therewith and having openings through it at right angles to each other and at right angles to the axis of the shaft, and a crank comprising a head having a vertical part and a horizontal part extending from said vertical part near its lower end in one direction, a crank pin extending from the lower side of said horizontal part downward, and a head on the lower part of said crank pin, a shank 85 extending from said vertical part in direction opposite from that of the horizontal part and adapted to pass through either one of said openings in said shaft head in either direction, a lip extending from said crank head in the same direction as the extension of the shank and adapted to engage with the lower side of said head to prevent the crank from turning with its shank in the opening in the shaft head, threads on the end part of said shank, a nut screwed 90 on said threads toward said shaft head to hold said crank to said shaft, and a connecting rod abutting said crank pin between the lower side of said crank head and the crank pin head, and a strap extending around the crank pin and having side parts flanking the connecting rod, and bolts through said connecting rod and said side parts, whereby said connecting rod is pivotally held to said crank.
25. In switch stand crank mechanism, in combination with a shaft, a rectangular head formed on said shaft integral therewith and having openings through it at right angles to each other and at right angles to the axis of the shaft, and a crank comprising a head having a vertical part and a horizontal part extending from said vertical part near its lower end in one direction, a crank pin extending from the lower side of said horizontal part downward, and a head on the lower part of said crank pin, a shank 95 extending from said vertical part in direction opposite from that of the horizontal part and adapted to pass through either one of said openings in said shaft head in either direction, a lip extending from said crank head in the same direction as the extension of the shank and adapted to engage with the lower side of said head to prevent the crank from turning with its shank in the opening in the shaft head, threads on the end part of said shank, a nut screwed 100 on said threads toward said shaft head to hold said crank to said shaft, and a connecting rod abutting said crank pin between the lower side of said crank head and the crank pin head, and a strap extending around the crank pin and having side parts flanking the connecting rod, and bolts through said connecting rod and said side parts, whereby said connecting rod is pivotally held to said crank.
26. In switch stand crank mechanism, in combination with a shaft, a rectangular head formed on said shaft integral therewith and having openings through it at right angles to each other and at right angles to the axis of the shaft, and a crank comprising a head having a vertical part and a horizontal part extending from said vertical part near its lower end in one direction, a crank pin extending from the lower side of said horizontal part downward, and a head on the lower part of said crank pin, a shank 105 extending from said vertical part in direction opposite from that of the horizontal part and adapted to pass through either one of said openings in said shaft head in either direction, a lip extending from said crank head in the same direction as the extension of the shank and adapted to engage with the lower side of said head to prevent the crank from turning with its shank in the opening in the shaft head, threads on the end part of said shank, a nut screwed on said threads toward said shaft head to hold said crank to said shaft, and a connecting rod abutting said crank pin between the lower side of said crank head and the crank pin head, and a strap extending 110 around the crank pin and having side parts flanking the connecting rod, and bolts through said connecting rod and said side parts, whereby said connecting rod is pivotally held to said crank.
